UNITED STATES PATENT OFFICE.

THOMAS SMITH, OF CORNELL, WISCONSIN, ASSIGNOR OF ONE-HALF TO HENRY C. FRISBIE, OF CORNELL, WISCONSIN.

METHOD OF PASTING AND MACHINE THEREFOR.

1,299,804.

Specification of Letters Patent.

Patented Apr. 8, 1919.

Application filed April 25, 1918. Serial No. 230,770.

To all whom it may concern:

Be it known that I, THOMAS SMITH, a citizen of the United States, residing at Cornell, in the county of Chippewa and State of Wisconsin, have invented certain new and useful Improvements in Methods of Pasting and Machines Therefor; and I do declare the following to be a full, clear, and exact description of the invention, such as will enable others skilled in the art to which it appertains to make and use the same.

My invention relates to improvements in methods and machines of the character employed for pasting a plurality of sheets of paper or the like together to form a multiple ply board used principally as a plaster substitute. In this form of machine, it has been found that a great waste of silicate or other paste used has taken place and it is to prevent such waste that I have devised the present invention.

With the foregoing object in view, the invention resides in the novel method and features of construction and unique combinations of parts to be hereinafter fully described and claimed, the descriptive matter being supplemented by the accompanying drawings which form a part of this specification and in which:

30 Figure 1 is a side elevation of a pasting machine embodying my invention;

Fig. 2 is a diagram showing more particularly the manner in which the "doctor" or scraper bar separates the filler sheets and at 35 the same time removes the surplus paste therefrom;

Fig. 3 is a front elevation of the machine with parts removed; and

Fig. 4 is a perspective view of the "doctor" 40 or scraper bar and its carrying arms.

In the drawings above briefly described, the numeral 1 designates a well known form of pasting machine embodying a pan 2 for the silicate or other paste, a roller 3 for 45 guiding the lowermost of the two filler sheets 4 through said pan, a pair of superimposed rolls 5 for pressing the two sheets 4 together and equally distributing the silicate or the like thereover, and a pair of 50 pressing rollers 6 which finally press the filler sheets and the two liner sheets 7 together, paste being applied to the upper surface of the uppermost filler sheet by a suitable nozzle 8. In this form of machine, an

additional roller is usually employed above 55 the rollers 5 for guiding the upper liner sheet 7, the supporting means for this roller rising from the bearings 9 of the upper roller 5. Due to the nature of the present invention however this additional roller is 60 omitted and the horizontal ends 10 of a pair of inclined arms 11 are bolted to the bearings 9 as seen at 12.

The lower ends of the arms 11 are turned substantially upon themselves to form a 65 pair of U-shaped sockets 13 of rectangular contour, the ends of said sockets snugly yet removably receiving therein the ends of a polysided "doctor" or scraper bar 14. This bar is located between the rollers 5 and 6 70 and serves to separate the two filler sheets 4 after passage thereof between said rollers 5, and while said sheets are thus separated, the bar 14 scrapes all surplus paste or the like therefrom. The several sheets then pass 75 between the rollers 6 and are securely pressed together by the latter to form the multiple ply board indicated at 15. Bolts 16 pass across the open sides of the sockets 13 to retain the bar 14 in place but by removing these bolts, the bar may be turned to present new scraping edges to the filler sheets, said bar being so located that two of its edges will engage said sheets while a third edge will be disposed toward the rolls 80 85 5 to assist in separating the two sheets.

By passing the filler sheets 4 between the rollers 5 after application of paste, and then separating said sheets to remove the surplus paste therefrom, much better results are obtained than when an attempt is made to remove the excess paste before passage of the sheets between the rolls. This is due to the fact that by pasting the two sheets together and then separating them, the surplus paste 90 95 will project from the inner surfaces of the sheets in a multiplicity of globules, and it is these globules that are scraped off by the bar 14. Bars of this general character are commonly known to the art as "doctors" 100 and I have therefore used this term herein. As far as I am advised, no "doctor" has ever been employed to separate two sheets of material previously pasted together and to remove the surplus paste while the sheets are 105 separated. This idea constitutes the gist of the present invention.

It is an easy matter to apply the "doctor"

14 to practically any of the well known types of pasting machines by removing the upper roller and its bearings, and substituting the arms 11. These arms are preferably constructed as shown and described but other forms may well be employed. In any case, the "doctor" 14 will be highly efficient for the purposes intended.

Although the operation of the machine as 10 a whole will probably be clear from the foregoing, it may be well to briefly set forth such operation. To this end, it may be pointed out that the lower filler sheet 4 is passed through the paste in the pan 2 to become 15 coated with such paste, said sheet then passing between the rollers 5 with the upper filler sheet 4 and thus applying the paste to the latter. At the same time, paste is applied to the central portion of the upper sheet 4, along its upper side, by the nozzle 8, and as the sheets pass between the rollers 5, this paste is spread evenly and at the same time the upper roll 5 applies the paste to the lower surface of the upper liner sheet 7. 20 The lower liner sheet preferably passes under the pan 2 as shown and is supplied with paste at the rolls 6 from the lower surface of the lower filler sheet 4. As the two filler sheets 4 leave the rolls 5, they are spread 25 apart by the "doctor" 14 and the surplus paste is removed from their inner faces. These sheets then travel to the rolls 6 however and are pressed firmly together by the latter, the liner sheets 7 being at the same 30 time applied to the outer faces of said filler sheets, whereby to form the complete board 15.

From the foregoing, taken in connection with the accompanying drawings, it will be 40 obvious that although my invention is of comparatively simple and inexpensive nature, it will be highly efficient for the purpose intended. Since probably the best results are obtained from the arrangement shown and described, such arrangement is 45 preferably employed, but within the scope of the invention as claimed, considerable latitude is allowed for application of the invention to different forms of machines. It is 50 also to be understood that although I have used the term "paste" in the foregoing and in the appended claims, this term is to be given a sufficiently broad interpretation to cover any of the well known viscous or glutinous

fluids commonly used in the manufacture of multiple ply board.

I claim:

1. A machine for uniting sheets of material to form a multiple ply board, comprising a pair of rolls between which the sheets pass, means for applying paste to said sheets before passage thereof between said rolls, means for separating said sheets and removing surplus paste therefrom after passage of said sheets between said rolls, and a pair of pressing rolls for again forcing said sheets tightly together after removal of the surplus paste.

2. A machine for uniting sheets of material to form a multiple ply board, comprising a pair of rolls between which the sheets pass, means for applying paste to said sheets before passage thereof between said rolls, a polysided scraper bar for separating the sheets and scraping surplus paste therefrom after passage of said sheets between said rolls, and a pair of pressing rolls for again forcing said sheets tightly together after removal of the surplus paste, said scraper bar having two of its corners disposed for contact with the separated sheets and a third corner disposed toward said first named pair of rolls to assist in separating said sheets.

3. A structure as specified in claim 2, together with a pair of rigid arms for supporting said scraper bar, one end of said arms being anchored and the other ends thereof being turned substantially upon themselves to form U-shaped sockets receiving the ends of said scraper bar, and bolts passing across the open sides of said sockets to retain said bar in place.

4. The method of pasting sheets of material together without waste of paste, consisting of applying the paste, pressing the sheets firmly together, separating said sheets after the pressing operation and at the same time removing the surplus paste, and again pressing said sheets tightly together after removal of the paste.

In testimony whereof I have hereunto set my hand in the presence of two subscribing witnesses.

THOMAS SMITH.
